TWO CYCLE ENGINE

Arthur G. S. Sherman, Detroit, Mich.

Application February 29, 1932, Serial No. 595,856

6 Claims. (Cl. 123—65)

This invention relates to internal combustion engines, and particularly to two-cycle engines.

While two-cycle engines have a decided advantage over four-cycle engines in simplicity of construction, cost of manufacture, the magnitude of power output for a given size of engine, and low upkeep expense, the four-cycle engine is largely preferred, in present day practice, because of its superior reliability, more economical fuel consumption, and adaptability to easy starting.

The disadvantages of the two-cycle engine primarily arise from use of the incoming fuel mixture to drive out spent gases by direct displacement. The resulting intermixture of the fuel charge and spent gases has heretofore unduly diluted such charge and permitted a considerable escape of unburned fuel during the concurrent periods of intake and exhaust.

Also it has been the general practice in two-cycle engine design to effect compression of the fuel mixture in the engine crank case, and this has rendered starting laborious through necessity of initially filling both the crank case and the cylinder with an explosive mixture. Crank case condensation of fuel, particularly prior to warming up of the engine, has also been a notable detriment.

An object of the invention is to make an improved provision for the admission of a charge to a two-cycle engine, whereby segregation of the incoming charge from the spent gases will be largely increased over present practice, with correspondingly large reductions in the residue of spent gases contaminating the charge as compressed, and in the escape of fuel with the spent gases.

Another object is to so admit the charge to a two-cycle engine as to maintain adjacent to the piston, throughout compression, a body of uncontaminated fuel, which, on completion of the compression stroke, will lie in such proximity to the ignition means as to insure ignition.

Still another object is to arrange the intake and exhaust ports of a two-cycle engine in an improved relation tending toward a more effective scavenging, and toward a minimum exhaust of unburned fuel.

A further object is to introduce the fuel charge into an internal combustion engine (and more particularly a two-cycle engine) at a velocity and pressure independent of piston travel whereby difficulty is avoided in supplying the engine with a thoroughly combustible charge

for starting, and crank case compression, with its well-known disadvantages, is eliminated.

These and various other objects the invention attains by the construction hereinafter described and illustrated in the accompanying drawings, wherein:

Fig. 1 is a view in axial sectional elevation of the improved engine, showing the intake and exhaust ports uncovered.

Fig. 2 is a similar view, showing the compression stroke completed, the charge being ready for ignition.

Fig. 3 is a cross sectional view, taken upon the line 3—3 of Fig. 1, and showing the piston in top plan.

Fig. 4 is a side elevational view of the engine.

In these views, the reference character 1 designates the cylinder of a two-cycle engine, 2 the crank case thereof, 3 the crank shaft, 4 the piston, and 5 the connecting rod. In the wall of said cylinder is formed an intake port 6 to which fuel may be delivered from any suitable source by way of a duct 7, and said wall is further formed with a pair of exhaust ports 8 and 8', preferably adjacent to and at opposite sides of the port 6. The piston 4 in its lower limiting position, (Fig. 1) is adapted to uncover all three ports 6, 8 and 8'.

The head of the piston 4 is diametrically formed with a fuel mixture passage 9 having an inlet in the lateral face of the piston, registerable with the port 6, when the piston is lowered. At its other end, said passage discharges into a pocket 10 opening both radially and upwardly in the piston head, and having a substantially vertical wall extending in an approximately 35 chordal relation to the piston, with preferably a slight curvature reentrant to the head. Preferably the top face of the piston inclines upwardly at a gradual angle (as for example twenty degrees) toward the pocket 10, and it is also preferred to flare the passage 9 transversely from its mid portion to its opening into said pocket, as best appears in Fig. 3.

Suitable ignition means upon the top portion of the cylinder is preferably positioned for registration with one or both extremities of the passage 9, when the engine is ready to fire. As illustrated, this ignition means comprises a pair of spark plugs 12 and 12' diametrically opposed upon the cylinder; registering respectively with the pocket 10 and the inlet of the passage 9, when the piston is raised.

To provide for uncovering of the exhaust ports 8 and 8' on completion of the power

stroke, the piston is preferably formed with a pair of pockets 13, one at each side of the inlet of the passage 9, each opening jointly in the top and lateral faces of the piston.

5 Delivery of fuel to the port 6 is accomplished independently of the engine crank case, and also of the piston stroke. Thus, preferably a blower 14 driven by an electric motor 15, delivers a stream of air at a suitable superatmospheric pressure to the port 6 by way of the duct 7 and in the latter is interposed a carburetor 16, which permits a predetermined amount of fuel to be entrained by the air stream, in finely divided form. Thus, in starting the engine, said motor and blower may be energized independently of the piston travel, so as to promptly fill the cylinder with a combustible mixture, and an adequate and proper mixture will be assured throughout operation of the engine.

10 20 Furthermore said mixture will be admitted at a considerably higher pressure and hence in considerably greater volume than is feasible where crank case compression is employed.

15 25 In operation of the described engine, the explosive mixture delivered to the passage 9 through the port 6, in the lowered position of the piston, is conducted by said passage across the piston head to the pocket 10. Encountering the cylinder wall in said pocket, the mixture is deflected along said wall to the upper end of the cylinder, and is there again deflected by the cylinder head across the latter. In this manner, the cylinder is rapidly filled with the fuel mixture, which accumulates from the cylinder top downwardly, and also to a slight extent inwardly from the side of the cylinder adjacent to the pocket 10. Since the inflowing mixture closely follows the cylinder wall, each increment of the charge of mixture displaces 30 previously delivered increments away from such wall and the cylinder top and toward the exhaust pockets 13, so that an initially delivered portion of the charge shields the balance of the charge from contact with the spent gases during complete scavenging of the latter. The spent 35 gases are displaced through the exhaust ports 8 and 8' by the incoming mixture and contamination of the latter is almost completely avoided in delivering the mixture as described, since the exhausting gases do not traverse the path 40 of any incoming mixture, nor does the latter materially penetrate the body of spent gases.

45 50 In thus avoiding contamination of the fuel mixture, delivery of the incoming mixture across the piston through a passage in the piston head is a vital feature. Employment of said passage permits the exhausting gases and incoming mixture to concurrently flow through closely adjacent ports, while positively and completely isolating said gases and mixture from each other in the vicinity of said ports, and maintains this isolation until the mixture has reached a point diametrically opposed to said ports.

55 60 Also said passage assures maintenance, during the compression stroke, of a portion of the mixture completely free of contamination in such a definite proximity to the piston head that prompt and certain ignition will take place on registration of said piston with the spark plugs, at the instant of firing.

65 70 Operation of two-cycle engines, as heretofore constructed, is often rendered defective by "four cycling", or firing only on alternate compressions. This is due to such impoverishment of 75 the compressed charge by spent gases as to re-

quire two such charges to support an explosion.

Such defective operation is eliminated in the described construction both by minimizing dilution of the entire charge and by transmitting combustion from the spark to a portion of said charge which is fully safeguarded from dilution. 5

It may be also noted that when crank case compression is employed, the charge is introduced into the cylinder under a continuously 10 varying pressure, whereas the means now disclosed maintains uniformity of fuel throughout the intake period.

The high pressure introduction of fuel is a factor of importance in preventing appreciable 15 mixing of the fuel and exhaust gases since the pressure imposes a velocity upon the incoming fuel such as carries it forcefully along the desired path without diffusion.

20 By flowing the fuel mixture through the piston head, as described, the fuel temperature is materially raised prior to ignition, thus facilitating combustion, and the piston is sufficiently cooled to safeguard it from heat damage.

25 While it is apparent that the illustrated embodiment of my invention is well calculated to adequately fulfill the objects and advantages primarily stated, it is to be understood that the invention is susceptible to variation, modification and change within the spirit and scope of 30 the subjoined claims.

What I claim is:

1. In a two-cycle engine, the combination with a cylinder formed with an intake and exhaust port, of a piston reciprocatory in said cylinder 35 and having an approximately diametrical intake passage opening at one end in the end face of the piston in close proximity to the cylinder wall, the other end of said passage being registrable on approximate completion of the power stroke 40 with said intake port, said piston being further marginally formed with an exhaust pocket opening upwardly and also opening toward the cylinder wall, registrable with said exhaust port on completion of the power stroke. 45

2. A two-cycle engine, comprising a cylinder having intake and exhaust ports, a piston reciprocatory in said cylinder having a fuel passage and having a pocket opening in the end face of the piston at the margin of said face, said passage having an inlet, opening laterally in the piston and having an outlet opening into said pocket, registrable with said intake port upon completion of the power stroke, said exhaust port being uncovered by the piston upon completion of the power stroke, and dual ignition means upon the cylinder registrable with said pocket and with the inlet of said passage upon completion of the compression stroke. 55

3. A two-cycle engine comprising a cylinder 60 having an intake port and exhaust port, and a piston reciprocatory in said cylinder, and having its head marginally formed with an intake pocket and an exhaust pocket, each opening upwardly and also opening toward the cylinder 65 wall, said exhaust pocket being registrable with said exhaust port, upon approximate completion of the power stroke, the piston being further formed with an intake passage, registrable at one end with the intake port upon approximate 70 completion of the power stroke, said passage opening at its other end into the intake pocket, toward the cylinder wall.

4. A two cycle engine comprising a cylinder, 75 a piston reciprocating in said cylinder, having

a fuel passage and an outlet to the cylinder from one end of said passage, means for delivering fuel to the other end of said passage in a substantially limiting position of reciprocation 5 of said piston, and dual ignition means upon the cylinder registerable with both ends of said passage substantially in the other limiting position of piston reciprocation.

5. In a two cycle engine, the combination with 10 a cylinder having an intake port, of a piston reciprocator in said cylinder and formed, in a substantially diametrical relation to the piston, with an intake passage registerable at one of its ends with said intake port, on approximate completion of the power stroke, said piston being further formed with a pocket connected to 15 the other end of said passage, opening toward the cylinder wall and also opening upwardly, said pocket being closed by the cylinder wall

at the sides of said passage, whereby the discharge of fluid from said passage is restricted to an upward direction along the cylinder wall.

6. In a two cycle engine, the combination with 10 a cylinder having an intake port, of a piston reciprocator in said cylinder and formed, in a substantially diametrical relation to the piston, with an intake passage registerable at one of its ends with said intake port, on approximate completion of the power stroke, said passage opening 15 at its other end in a wall of the piston which wall extends between circumferentially spaced points of the cylinder wall, and forms with the cylinder wall a pocket opening only in an upward direction, whereby fuel discharging from said pocket is limited to an upward direction and restrained in its tendency to diffuse.

ARTHUR G. S. SHERMAN.
